BASEBOARD RADIATOR

Chester M. Wilcox, Allentown, Md.

Application May 1, 1950, Serial No. 159,234

4 Claims. (Cl. 257—133)

1

This invention relates to heat exchangers and more specifically to radiators of the base board type.

An important object of the invention is to provide a radiator consisting of a plurality of interconnected parts whereby the size of the radiator may be adjusted to fit various situations.

Another important object is to provide such a radiator which may be adjusted horizontally along a wall as well as vertically so as to embody one or two horizontal cores disposed in parallelism.

A further important object is to provide a base board radiator which may have its supply and return at opposite ends, both at one end, or disposed at points intermediate the ends, thus permitting installations to take the place of conventional radiators of various makes and models, without tearing up floors in order to rearrange the supply and return conduits.

With a view of providing for the best circulation of air through the base board radiator, an important object of the invention is to provide a bottomless housing, raised above the floor, with the support means for the cores so constructed and arranged that the air circulation is not interfered with thereby, and an upper opening with an adjustable damper so disposed that a regulated volume of warm air will be discharged into the room.

Another important object is to provide for movement of the core supports to compensate for longitudinal expansion and contraction of the cores.

Since the installation comprises a desired number of the new base board radiator units, damper adjustments may be made to discharge one volume of warm air into one part of a room and a different volume into another part.

Furthermore, an important object is to provide interlocking end walls, which may be detachably secured to the rear and upper wall sections of the radiator housing.

Other objects and advantages of the invention will be apparent during the course of the following detailed description of the invention, taken in connection with the accompanying drawings forming a part of this disclosure and in which drawings:

Fig. 1 is an elevation of the new base board radiator, with parts of a housing thereof broken away in order to reveal portions of the structure beneath.

Fig. 2 is a vertical section of the new radiator, with a damper open.

2

Fig. 3 is a section, substantially on the line 3—3 of Fig. 5.

Fig. 4 is a fragmentary horizontal section, on an enlarged scale, substantially on the line 4—4 of Fig. 1.

Fig. 5 is a vertical section, substantially on the line 5—5 of Fig. 6.

Fig. 6 is a vertical transverse section of the upper portion of the radiator housing, with the damper removed.

Fig. 7 is a perspective of an end wall of the housing.

Fig. 8 is a perspective of a fragment of the housing, with end wall removed.

Fig. 9 is a fragmentary perspective of support or bracket for a core or cores and a securing means for retaining the damper in adjusted position.

Fig. 10 is a perspective of the damper.

Fig. 11 is a fragmentary horizontal section through an offset for supporting the damper in various positions and for supporting a front wall of the housing.

Fig. 12 is a view in horizontal section of a fragment of the rear wall of the housing showing the lower portion of the support or bracket of Fig. 8, supporting a latch means to the front wall of the housing.

In the drawings wherein for the purpose of illustration is shown a preferred embodiment of the new radiator, the letter A designates a portion of a building structure; B, heating installations; and C, the novel radiator.

For the purpose of illustration, there is shown a portion of a building structure A including a floor 15 and vertically disposed wall 16 extending to the floor 15. There is also shown base board trim 17 and 18, which may be portions of a conventional base board, shown at 19 in dots-and-dashes, in Fig. 2, since where the novel radiator is installed in a building already erected, a portion or all of this conventional base board is removed, and only the trim 17 and 18, for example, retained. In installations in buildings being erected, the conventional base board, or portions of it, are eliminated and suitable trim such as 17 and 18 employed in conjunction with the new base board radiator C.

Obviously, the heating installations B may vary and include, for example, the risers 20 and 21 of Figure 1, with elbow 22 and T-coupling 23 with convention air valve 24. In the example shown in Fig. 1, both risers are near one end of the installation.

55 The new base board radiator C comprises a

housing 30, damper 31, a core or cores 32, brackets 33 for the core or cores, and securing means 34 for retaining the damper in adjusted positions. Means 35 may be employed to secure the housing 30 to the wall 16, and means 36 is preferably provided to latch a front wall of the housing to the rear wall thereof.

Referring first to Fig. 8, the housing 30 includes a rear wall 40, comprising a vertical section 41, from which extends an upper wall or horizontal section 42 extending forwardly from the upper end of the section 41, a downturned, preferably narrow section 43 at the forward end of the section 42, a preferably narrow horizontal section 44 substantially paralleling the section 42 and extending inwardly from the lower end of the section 44 and an upturned flange section 45 at the inner end of the section 44 extending toward but free of the section 42. The sections 43, 44 and 45 with the adjacent part of the section 42 provides a channeled member for swingably retaining the upper end portion of the damper 31 to be described. Extending along the inner or lower face of the section 42 at the outer end portions of this section are tongued members 46 (one being well shown in Fig. 5). Each of these may have an attaching flat portion 47 welded or otherwise secured to the section 42 and a stepped portion 48 providing an outwardly extending tongue spaced below the adjacent portion of the section 42, with its outer free end edge in substantially the same vertical plane as the end edge of the associated section 42. This provides a recess to accommodate a flange of the end wall 60 to be described. Similar tongued members 49 having flat portions 50 and tongued portions 51 may be secured to the wall section 41 at the end edge portions thereof to provide recesses for receiving other flanges of the end walls 60 as will be described.

The housing 30 also includes a front wall 55 comprising a vertically-disposed main wall section 56, an L-shaped flange 57 at its upper end and an inwardly and upwardly extending flange 58 at its lower end forming a V. The wall section 56 is of less height than the wall section 41, as may be seen in Fig. 8 and, when assembled with the other wall sections, its upper end is spaced from the upper wall section 42, the space providing a warm air exit 59 (Fig. 2) while its lower end is spaced from the floor 15 providing an air entrance.

There is, preferably, no bottom wall to the housing.

Each end wall 60, shown particularly in Fig. 7, comprises a vertical wall section 61 having a rear flange 62 preferably extending from the bottom edge of the wall section 61 to the upper edge thereof but having a diagonal cut out 63 at adjacent this upper edge (portions of which flange 62 extend into the recess defined by the tongued portion 51 and adjacent wall section 41) an upper flange 64 (which extends into the recess defined by the wall section 42 and stepped portion 48) and a front flange 65 which has a cutout 66 to accommodate the end portion of the damper 31 and flange 57 which latter rests upon the lower edge of the cutout. The flange 65 ends short of the lower end of the wall section 61 so as to accommodate the flange 58 which slips into the V defined by this flange and the adjacent wall section 56, and is in frictional engagement therewith at the juncture of flange 58 and wall section 56. In the same way the upper end edge portion of the flange 65 extends into the channel formed by the flange 57 and adjacent wall section 56. It will

be noted that there is a small tongue 67 of the flange 65 above the cutout 66 and this is adapted to snugly fit into the channel formed by the sections 42, 43, 44 and 45. This association of parts 5 frictionally retains the end walls 60 to the wall sections mentioned, and when the end walls 60 are in place the housing defines a chamber to accommodate the damper 31, core or cores 32, brackets 33, and risers 20 and 21 with their fittings. The housing may be of sheet steel or like material.

The damper 31, best shown in Fig. 10, comprises a wall section 70 of a length and width so that when hanging vertically it will completely close 15 the warm air exit 59. It has at its upper end an outwardly and downwardly extending flange 71 which is adapted to project into the channeled member defined by the sections 43, 44 and 45 and adjacent portion of the section 42, there being 20 an up-and-down play of the flange 71 therein so that the flange may be inserted into the channel. When the damper is vertical its lower edge 72 will abut the flange 57. Suitable handles or hand 25 holds 73 may be secured to the outer face of the wall section 70 to project forwardly thereof. The damper may be of sheet steel.

The core or coil assembly of Fig. 1 is preferably composed of a plurality of conventional radiator cores or coils 32. Such cores or coils may be assembled end for end as required, since the ends telescope. They are finned as at 75 with the fins spaced apart, providing recesses, and extending from a central tube 76. The terminal tubes at one end of the assembly are secured, as is well known in the art to the couplings 22 and 23 and the terminal tubes at the other end of the assembly are secured, as is well known in the art, to an elbow 77 or the like.

One of the brackets 33 for the cores 32 is shown 40 specifically in Figs. 2 and 9 and comprises two spaced-apart, horizontally disposed arms 80 and 81, one above the other and joining a vertically disposed arm 82 which extends, as at 83, preferably slightly upwardly beyond the arm 81. The 45 bracket 33 may be of stamped thin sheet steel and the end edges of the free ends of the arms 80 and 81 are adapted to abut a face of a bracket holder 84 while the adjacent portion of these free ends have downwardly opening slots 85 which hook over tongues 86 projecting upwardly from and away from the holder 84, being preferably struck from the material (sheet steel, preferably) of the holder. The tongues are fairly wide (as, for example one-half inch) so that the brackets 50 may slide along the tongues and swing as the cores expand and contract. The arm 80 is adapted to be positioned between two adjacent fins 75 of a core as in Fig. 2, and, if a second core is employed above the first, the arm 81 is adapted 55 to fit between two adjacent fins 75 of the latter core, with the arm 82 also between the fins of the first core and the arm portion 83 between the fins of the core above it. A core may be mounted upon a bracket between the arms 80 and 81 by 60 slipping it into the opening at the free ends of the arms. A core above it may be slipped over the arm 81 and with the projection 83 between two fins.

Any suitable means may be provided to secure 70 the bracket holder 84 to the wall section 41. For example, the bracket holder 84 may carry an inverted keyhole slot 87 for a headed screw (not shown) extending through a suitable opening in the wall section 41, or welding 88 may be employed, as in Fig. 11.

5

This bracket holder 84 preferably carries the securing means 34 for retaining the damper 31 in adjusted positions and is shown in Figs. 2 and 9. This may be a horizontal offset 89 from one edge of the holder 84 projecting toward the front wall section 56 and disposed at the upper portion of the holder. The offset is provided with a plurality of stepped abutments, such as 90, 91 and 92, which are adapted to receive the free end portion of the damper with a part of the edge 72 resting against any selected abutment. There is a defined slot 93 at the lowermost portion of the offset having a curved lug 94 along the rear edge of the slot and adapted to springingly retain the front wall 55, as in Fig. 11 when the latter section is in position and has a portion of the flange 57 in the slot 93, thus assisting in preventing vibrations or swinging of the front wall section 56.

The means 35 may be suitable headed nails, shown in Fig. 2, extending through suitable aligning perforations preferably in the rear wall section 41 and bracket holder 84, and with their free ends extending into the wall 16.

In Figs. 2, 9 and 12 is shown means 36 to latch the front wall 55 to the rear wall 40 in order to further prevent oscillations of the former. This means comprises a swinging member 95 preferably of resilient wire, formed with an inverted L-shaped rear portion 96, a bowed intermediate portion 97 and a hook-like front portion 98 with the latter adapted to be manually hooked over the flange 58 of the front wall 55. This member 95 is swingably carried, to swing horizontally, by a bracket holder 84 as by slitting and upsetting the material of the same to provide a knuckle 99 adapted to receive the larger part of the portion 96 as a pivot for the member 95. In shipping the knocked down radiator housing, the member 95 may be swung to the dotted position in Fig. 12 but manually brought to the full line position in order to employ it, as is now obvious.

The swinging of the brackets 33 is of major importance since the cores generally heat up quickly and expand longitudinally. It has been discovered that, because of ability of the brackets to swing, the fins are not bent, torn loose nor otherwise damaged, nor do the core bodies buckle. On the other hand expansion and contraction of the cores does not tear the brackets loose from their supports.

The most forward edges or faces of the offsets 89 are in substantially the same vertical plane and these edges are adapted to abut the inner face of the front wall section 56, thus aiding in the rigidity of the radiator housing.

The housing sections, preferably being of sheet steel may be readily cut to size in the event it is not possible to employ, for example, three complete units. Since the rear wall 40 is fixed to the wall 16 as by the means 35, the rear wall may be abbreviated longitudinally and abut the adjacent rear wall, as in Fig. 4. The conventional cores are also generally adapted to be cut to length.

In the event but a single run of cores is desired, the elbow 71 of Fig. 1 may be continued, as conduit (not shown) to parallel the cores and be disposed upon the arms 81. This conduit may, of course, connect with the T-coupling 23.

6

The damper 31 is hung by slipping its flange 71 over the section 45, and the front wall 55 is supported by the offset 89 which, thus, has dual functions since it also provides the means 34.

Various changes may be made to the form of the invention herein shown and described without departing from the spirit of the invention or scope of the claims.

What is claimed is:

1. A baseboard radiator employing a heated fluid-containing core having spaced-apart fins, a housing for the core, including a wall section, and suspension means for the core comprising a substantially straight horizontal row of spaced-apart bracket holders removably secured to and extending from said wall section including upwardly-projecting pairs of tongues extending into the housing, the tongues of each pair being substantially directly one above the other, and a core-supporting bracket for each pair of tongues, said bracket having a pair of spaced-apart arms, each arm being provided with a downwardly-opening slot to receive a tongue in a substantially horizontally-swinging relationship of said arms with said tongues when a coil is supported by said bracket, and connecting means rigidly connecting the pair of arms in substantial parallelism.
2. A baseboard radiator according to claim 1 characterized in that said arms are substantially straight and flat throughout their lengths and are of a thinness so that one of said arms may be readily inserted between adjacent fins of the core.
3. A baseboard radiator according to claim 1 characterized in that said arms have upper core-supporting edges and lower edges with said slots extending into said lower edges and being remote from said connecting means.
4. A baseboard radiator according to claim 1 characterized in that said bracket is a thin, substantially flat metallic member, said connecting means comprises an arm, and said pair of arms is spaced-apart substantially parallel and straight, and secured to and disposed substantially normal to the first arm, said pair of arms being provided with core-supporting edges and edges substantially parallel thereto, with said slots extending into the last-named edges and being remote from said first arm.

CHESTER M. WILCOX.
